(57) **CLAIM**

The ornamental design for a cover for tape cartridge, as shown and described.

DESCRIPTION

FIG. 1 is a front view of a cover for tape cartridge;
FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a perspective view thereof; and,
FIG. 8 is a perspective view thereof showing the cover installed on a tape cassette case with a tape spool support mounted in the case.

The broken line showing of a cartridge is for illustrative purposes only and does not form part of the claimed design.
